UNITED STATES PATENT OFFICE

DAVID C. BETTISON, OF OMAHA, NEBRASKA

ELECTRICAL APPARATUS

Application filed July 22, 1927. Serial No. 207,610.

My invention relates to electrical apparatus, and particularly to apparatus for at times supplying a load with both alternating and direct current. My invention is particularly adapted for, though in no way limited to, use in railway traffic controlling systems in which both alternating and direct currents are supplied to the trackway.

I will describe several forms of apparatus embodying my invention, and will then point out the novel features thereof in claims.

In the accompanying drawing, Fig. 1 is a diagrammatic view showing one form of electrical apparatus embodying my invention. Figs. 2, 3 and 4 are views showing modified forms of the apparatus shown in Fig. 1 and also embodying my invention.

Similar reference characters refer to similar parts in each of the several views.

Referring first to Fig. 1, the reference characters 1 and 1' designate the track rails of a stretch of railway track along which traffic moves in the direction indicated by the arrow. These track rails are divided, by means of insulated joints 2, into a plurality of successive track sections A—B, B—C, etc. Each track section is provided with a track relay designated by the reference character R with a suitable distinguishing exponent and connected across the rails of the corresponding section. Each track relay R is intended to operate upon direct current, and is not responsive to alternating current flowing therethrough. For supplying direct current to the rails of the track section for the control of the track relays R, a track battery is connected across the rails adjacent the right-hand end of each section, each such battery being designated by the reference character D with an exponent corresponding to the location.

Means are also provided for at times supplying each track section with alternating current which may be used to control train carried governing means not shown in the drawing. For present purposes it will be sufficient to state that when the section of track occupied by the train is being supplied with alternating current, a proceed indication is received on the train and when the supply of such alternating current to the track-

way is for any reason interrupted, a stop indication is received on board the train.

In the present embodiment of my invention, the source of alternating current for each track section is a track transformer designated by the reference character T with a suitable distinguishing exponent, and having a primary 4 supplied with energy from secondary 10 of an associated line transformer K over a front contact 9 of the track relay R for the section next in advance. The primary 11 of each line transformer K is constantly supplied with alternating current over line wires 30 and 30^a from a suitable source of energy such as an alternator G. The primary 3 of each track transformer T is connected across the rails of the corresponding section in series with the associated battery D and the usual reactor 5 and resistor 6.

With the arrangement thus far described it will be seen that each track battery D constantly supplies direct current to the rails of the corresponding section so that each of the track relays R is energized at all times except when the section is occupied by a train. Furthermore, alternating current is supplied to the rails of each section in series with the corresponding track battery D at all times except when the track relay for the section next in advance is de-energized.

As shown in the drawing, a train indicated diagrammatically at V occupies the section to the right of point C, so that relay R^c is de-energized, with the result that the primary circuit of transformer T^c is open at front contact 9 of relay R^c, so that no alternating current is supplied to the rails of section B—C. The current supplied to section B—C from battery D^c energizes relay R^b, so that both alternating and direct currents are supplied to the rails of section A—B.

In many instances the track batteries D shown in the drawing are primary batteries. Since these batteries are constantly connected with the track rails, the drain upon the batteries is continuous, and considerable expense and inconvenience are entailed in the frequent replacements thus made necessary.

I therefore propose to reduce the amount of energy which must be supplied by each

track battery D by connecting an asymmetric unit 7 in series with a small resistance 8 across each track battery D and the secondary 3 of the corresponding track transformer 5 T. Referring for example to the apparatus located at point B, during one half of each cycle of current from transformer T^B this current tends to flow through battery D^B in the same direction as the current supplied 10 by this battery, and during this half cycle the asymmetric unit 7 offers a comparatively high resistance to the flow of current from the transformer through the unit. During the other half of each cycle, however, a considerable current flows from the transformer through unit 7 and battery D^B, it being noticed that the direction of the current through the battery D^B under these conditions is contrary to the direction of the current 15 supplied by the battery. During this half cycle there is applied across the terminals of battery D^B, a uni-directional electromotive force, which may be varied by variation of the resistance 8 to be of such value 20 that the energy which flows into the battery during this half cycle is substantially equal to the energy which flows out of the battery during the succeeding half cycle, and hence the net effect is that during a complete cycle 25 substantially no energy is permanently taken from the battery. Under these conditions, however, the current in the rails of section A—B has a uni-directional component due to the uni-directional electromotive force existing across the unit 7 and resistance 8.

As a result of this arrangement, the drain upon the track battery D^B is materially reduced, because, during at least a portion of each cycle of the alternating current supplied 40 by the transformer T, the flow of current from the battery D^B is opposed, without interference with the direct current component of the energy supplied to the trackway. The track relay R therefore operates in exactly 45 the same manner as it would without the asymmetric unit 7 connected in the circuit; but the total amount of energy required to be supplied by the battery D is materially reduced.

50 Of course, when the contact 9 of relay R^B is open, no alternating current is supplied to the section A—B by transformer T^B, and under these conditions, the entire amount of direct current supplied to the rails of section A—B must be furnished by the battery D^B. But even in systems where the trackway is used by a large number of trains, the circuit for any given transformer T is open for only a comparatively insignificant portion 55 of the time and I have discovered that a track battery provided with an asymmetric unit connected in the manner shown in the drawing will furnish the current required for the proper operation of the track relay 60 with only a very small fraction of the drain

upon the battery that occurs when the asymmetric unit is omitted.

Another reason for the increased life and saving in energy required by the primary battery, is that while it is generally true that 70 primary batteries cannot be "charged" in the same sense that secondary batteries can be charged, yet by the passage of current through the battery in the direction opposite to that of the current normally supplied by the battery, I have observed that some of the active material utilized during the supply of energy by the battery is replaced on the electrodes by the brief surges of energy which flow through the battery in the "charging" direction with the apparatus embodying 75 my invention.

Referring now to Fig. 2, with the arrangement here shown, the secondary 3 of transformer T is provided with the mid-tap a. 80 The right-hand portion of this transformer secondary supplies the alternating current to the track rails for operating the train carried governing means, and the asymmetric unit 7 and the resistance 8 are connected across the entire secondary 3 and the battery D. The advantage of this arrangement is that a larger uni-directional electromotive force is available across the terminals of the battery D to oppose the normal flow of current supplied by this battery during the half cycles in which the current supplied by transformer T tends to oppose the current normally supplied by the battery D. The operation of the apparatus illustrated in this view 85 will be readily understood without further explanation.

In the modification illustrated in Fig. 3, a first secondary 3^a of the transformer T supplies alternating current to the track rails 105 in series with the battery D. A second secondary 3^b of the transformer T has its mid-point connected with one terminal of the battery D, and has its two terminals connected through asymmetric units 12 and 13, respectively, with the opposite terminal of the battery D. When contact 9 of relay R is closed so that transformer T is energized, a uni-directional electromotive force is constantly applied across the terminals of the battery D in such direction as to oppose the flow of current from this battery into the circuit normally supplied with energy by the battery. With this arrangement, as long as transformer T is energized, there will be substantially 110 no drain upon the battery D, although the current in the trackway has a uni-directional component as a result of the uni-directional electromotive force applied across the terminals of the battery D by the energy 115 supplied by secondary 3^b.

In the modification shown in Fig. 4, the asymmetric unit 7 is connected directly across the battery D and the resistance 6. During 120 the half cycles in which the current from 125

transformer T tends to flow in the direction opposite to that of the direct current supplied by battery D, substantially no current flows through unit 7. During half cycles of the opposite polarity, however, while current from transformer T flows through battery D, it also flows through unit 7, so that the total current in the transformer secondary 5 is greater during the half cycles that current flows through unit 7. It follows that the current actually supplied to the track rails is unbalanced, that is, this current has a direct current component which is effective to operate the relay R connected across the 10 track rails. During the half cycles that the current does flow through the unit 7 in appreciable quantities, the potential drop across this unit is opposed to the current through battery D and the current furnished by the 15 battery is therefore reduced. As a result, a substantial saving is effected in the current supplied by battery D, and hence in the drain upon the battery and its life is correspondingly increased.

20 Although I have herein shown and described only a few forms of electrical apparatus embodying my invention, it is understood that various changes and modifications may be made therein within the scope of the 25 appended claims without departing from the spirit and scope of my invention.

Having thus described my invention, what I claim is:

1. In combination with a load, a battery 35 normally supplying direct current to the load, a source of energy supplying alternating current to the load in series with the battery, and an asymmetric unit connected in circuit with the battery and effective during alternate half cycles of said alternating current 40 to oppose the flow of current from the battery without substantially varying the direct current component of the current flowing through the load.

2. In combination with a load, a source of alternating current, a battery connected in series with the load and the source, and an asymmetric unit connected across said battery and said source.

3. In combination with a section of railway track, a source of alternating current connected across the rails of the section, a battery connected between the source and one rail, and an asymmetric unit connected in 55 parallel with said battery and source.

4. In combination with a section of railway track, a primary battery connected across the rails of the section, a source of alternating current connected in series with said battery, and an asymmetric unit connected across the source and battery in such manner as to permit current from the source to flow through the unit and the battery in a direction contrary to the direction of the current 60 supplied by the battery.

5. In combination, a section of railway track, a transformer having its secondary connected across the rails of the section, means for at times supplying alternating current to the primary of said transformer, a primary battery connected in series with said secondary and a rail of the section, and means including an asymmetric unit and receiving energy from said primary for causing a current to flow at times through the battery in 70 a direction contrary to the direction of the current supplied by the battery.

6. In combination with a load, a battery connected with the load, a source of alternating current for supplying alternating current to the load in series with the battery, and an asymmetric unit connected across said source and battery and disposed in such manner as to offer its higher resistance to current tending to flow from the battery through such 80 unit and the source.

7. In combination with a section of railway track, a transformer having its primary supplied with alternating current, a primary battery having one terminal connected with 90 one point on said secondary, means for connecting the free terminal of the battery with one rail of the section, means for connecting a second point on the secondary with the other rail of the section, and means including 95 an asymmetric unit for connecting a third point on the secondary with said free terminal of the battery, said unit being connected in such manner as to oppose the flow of current supplied by the battery through the unit 100 and said secondary.

In testimony whereof I affix my signature.

DAVID C. BETTISON.
